UNITED STATES PATENT OFFICE.

ETTORE BELLINI, OF ENGHIEIEN LES BAINS, FRANCE.

APPARATUS FOR DIRECTED WIRELESS TELEGRAPHY AND TELEPHONY.

1,297,313.

Specification of Letters Patent. Patented Mar 18, 1919.

Original application filed June 19, 1915, Serial No. 35103. Divided and this application filed October 19, 1916. Serial No 126,562.

To all whom it may concern:

Be it known that I, ETTORE BELLINI, subject of the King of Italy, residing at 41bis Boulevard Cotte, Enghien les Bains, Seine and Oise, in the Republic of France, have invented new and useful Improvements in Apparatus for Directed Wireless Telegraphy and Telephony, of which the following is a specification.

10 The present application is a division of my co-pending application for Letters Patent Serial No. 35103 filed on the 19th June, 1915, and patented April 3, 1917, No. 1,221,787.

15 The invention forming part of this application has for its object to provide wireless telegraph and telephone apparatus which allows, in regard to transmission, of controlling the direction of maximum projection of 20 electromagnetic waves, without turning the antennæ, and in regard to reception of making adjustment for reception from selected directions and ascertaining the direction of the transmitting station also without moving 25 the antennæ.

The apparatus essentially comprises pairs 30 of fixed conductive plates arranged around an axis, diametrically opposite each other, the number of pairs being equal to the number of aerials for directed waves, and the two opposed plates of each pair being connected to one of the aerials. Opposite the fixed conductive plates are arranged rotatable conductive plates directly or indirectly 35 connected to high frequency apparatus such as a sparking device, an arc, an alternator, or a detector. These rotatable plates are mechanically connected to each other, and can be rotated about the axis of the fixed system, 40 so that they can be placed opposite the two plates of any of the fixed pairs, or in any intermediate position. The fixed conductive plates and the movable conductive plates are arranged in co-axial cylinders, a short distance apart. The fixed or the movable plates 45 are preferably given special shapes, as will be described hereinafter.

The invention is illustrated in the annexed drawings, given as an example.

50 Figure 1 shows one form of construction of the apparatus.

Figs. 2 and 3 show two kinds of movable plates which can be used with the construction shown in Fig. 1.

55 Fig. 4 shows a perspective view of the ap-

paratus, the front fixed plate thereof being in part broken away in order to show the inside.

The apparatus shown in Fig. 1 comprises two pairs of conductive metal plates *a*, *a*, *b*, *b*, arranged upon a cylindrical surface, the plates belonging to each pair being diametrically opposite each other. These plates are in the form of rectangles and almost entirely cover the cylindrical surface; between them is left only sufficient space for insulation. The two diametrically opposed sectors *a* *a* are connected to an aerial 1 for directed waves, and the two sectors *b* *b* are connected to a similar aerial 2 perpendicular to the aerial 1. Each of these aerials may be formed in the well known manner, either by a couple of vertical antennæ, or by a frame, or by any type of directed wave aerial which radiates and receives with the maximum intensity in its own plane.

Inside or outside the cylinder formed by the fixed plates *a* *a* *b* *b*, there is a rotary system consisting of two plates *c*, mechanically connected together, but insulated from each other. These plates may have any form whatever but it is preferable to give them a form which, when extended in a plane, has an outline formed by two sinusoidal curves (Fig. 2) or by the portion of the inclosed surface situated above the axis of the abscissæ *s*—*t*. The two plates *c* must not touch each other, but must be very close together. G, H, I, J, (Fig. 2) designates the approximate outline of the four sectors *a* *a*, *b* *b* of the fixed system developed in plan. For greater clearness, however, this figure represents the development of the projections of the outer sectors on the cylindrical surface containing the rotary plates and not the exact development of the said sectors. These sectors have, preferably, a length *l* greater than the height *h* or *h'* of the sinusoidal curves. The movable sinusoidal cylindrical plates rotate about the axis *o* common to the fixed and rotatable cylinders.

Fig. 4 represents a perspective view of the apparatus, the front fixed plate thereof being in part broken away in order to show the interior of the apparatus. 1, 1 and 2, 2 are two directive aerials placed at right angles and respectively connected to the fixed plates *a*, *a* and *b*, *b*. The movable plates *c*, *c* are fixed to the insulating drum.

d, which can turn around the spindle *e*. The flexible leads *f*, *f* connect the movable plates to the detector *g* and the telephone *h*.

Instead of using two aerials at 90° to each other, I may, of course, use three aerials at 60° , or generally speaking n aerials at $\frac{360^\circ}{n}$, the number of pairs of fixed sectors varying accordingly. The movable system of the apparatus is connected in the well known manner to the oscillation generating or utilizing apparatus. Fig. 1 shows the movable plates connected to an oscillation generating circuit comprising a condenser *d*, an induction coil *i*, and a spark gap. A plurality of systems of fixed and movable plates may be superposed or arranged concentrically, in order to increase the capacity of the apparatus.

20 Having now described my invention, what I claim as new and desire to secure by Letters Patent is:

1. An apparatus for wireless telegraphy or telephony, comprising in combination 25 aerials for the reception or transmission of directed waves, fixed conductive plates arranged about an axis, so as to lie upon a cylindrical surface diametrically opposite each other in pairs, the number of pairs 30 being equal to the number of directed aerials, and the two plates of each pair being connected to one of the aerials, a rotary system of conductive plates mechanically connected together bent so as to lie upon a cylindrical 35 surface coaxial to that of fixed plates and adapted to rotate about the axis common to the two cylinders, and a high frequency apparatus, to which the rotary system of conductive plates is connected substantially as 40 described and for the purpose set forth.

2. An apparatus for wireless telegraphy or telephony comprising in combination aerials for the reception or transmission of

directed waves, fixed conductive plates arranged to lie upon a cylindrical surface, 45 diametrically opposite each other in pairs, the number of pairs being equal to the number of directed aerials, and the two plates of each pair being connected to one of the aerials, a rotary system of conductive plates 50 mechanically connected together bent so as to lie upon a cylindrical surface coaxial to that of the fixed plates, and adapted to rotate about the axis common to the two cylinders, said rotary plates having an outline 55 given by two sinusoidal curves of opposite phases, and a high frequency apparatus, to which the rotary system of conductive plates is connected, substantially as described and for the purpose set forth. 60

3. An apparatus for wireless telegraphy or telephony, comprising in combination aerials for the reception or transmission of directed waves, fixed conductive plates arranged to lie upon a cylindrical surface, diametrically opposite each other, in pairs, the number of pairs being equal to the number of directed aerials and the two plates of each pair being connected to one of the aerials, a rotary system of conductive plates mechanically connected together bent so as to lie upon a cylindrical surface coaxial to that of the fixed plates, and adapted to rotate about the axis common to the two cylinders, said rotary plates having a sinusoidal outline, and a high frequency apparatus, to which the rotary system of conductive plates is connected, substantially as described and for the purpose set forth. 75

In testimony whereof, I have signed my 80 name to this specification in the presence of two subscribing witnesses.

ETTORE BELLINI.
